US0D1011218S

(12) **United States Design Patent** (10) Patent No.: **US D1,011,218 S**
(45) Date of Patent: ** Jan. 16, 2024

(54) **ASPIRATED SMOKE DETECTOR**

(71) Applicant: **Siemens Schweiz AG**, Zurich (CH)

(72) Inventor: **Patrick Odermatt**, Zug (CH)

(**) Term: **15 Years**

(21) Appl. No.: **35/515,759**

(22) Filed: **Nov. 24, 2022**

(80) **Hague Agreement Data**

Int. Filing Date: **Nov. 24, 2022**

Int. Reg. No.: **DM/225146**

Int. Reg. Date: **Nov. 24, 2022**

Int. Reg. Pub. Date: **Dec. 9, 2022**

(51) **LOC (14) Cl. 10-05**

(52) **U.S. Cl.**

USPC **D10/106.2**

(58) **Field of Classification Search**

CLAIM

The ornamental design for an aspirated smoke detector, as shown and described.

DESCRIPTION

2. Smoke detector

2.1 is a front view

2.2 is a top view

2.3 is a bottom view

2.4 is a left side view

2.5 is a right side view

2.6 is a rear view.

2.7 is a front perspective view

2.8 is a rear perspective view

1 Claim, 8 Drawing Sheets
